LOCK CORNER SHINGLE

John V. Donahue, Kokomo, Ind., assignor to
 United States Gypsum Company, Chicago, Ill.,
 a corporation of Illinois

Application November 19, 1931
 Serial No. 576,147

4 Claims. (Cl. 108—7)

This invention relates to composition roofs formed by laying individual shingles one by one to have the last laid shingle interlock by a corner with a shingle to the left thereof. It is a primary object of the invention to so form the individual shingle that the lower exposed edge thereof is secured to the roof deck in such a manner that it will not be lifted by wind pressure either directly under the lower horizontal edge 5 or from an exposed vertical edge thereof.

An important object of the invention is to provide an individual shingle which may be cut without waste and without the necessity of having to cut out small pieces thereof which are apt 10 to become embedded on the faces of the shingles in placing them in packages for shipment, and which precludes the necessity of having to form intricate dies and for matching one edge of the shingle with a corresponding edge of another in 15 the roll of material from which they may be cut.

A further important object of the invention is to form a simple lock between adjacent shingles in the same horizontal row whereby the minimum amount of any one shingle is required to 20 be inserted under a shingle previously nailed down and also whereby a lock is formed between the two shingles which will prevent the lifting of the lower corner of that shingle which corner 25 is not directly nailed to the deck.

These and other objects and advantages will 30 become apparent to those versed in the art by the following description of the invention which is made in reference to the accompanying drawing in which

Fig. 1 is a top plan view of a shingle embodying my invention:

Fig. 2, a diagrammatical representation of how 35 shingles embodying my invention may be cut from a strip of material:

Fig. 3, a plurality of shingles laid together to 40 form a roof covering and

Fig. 4, a similar view of a group of shingles 45 laid to form a roof covering but to have less lap and more exposure.

Like characters of reference indicate like parts in the several views in the drawing.

It being an object of my invention to form a shingle that may be initially inexpensive and 50 also that may be laid at the lowest possible cost, I form individual shingles 10 essentially rectangular in shape and from the lower edge of each shingle spaced a short distance from the right hand corner thereof I cut the shingle 55 vertically upwardly from that lower edge to form

a slit 11 without removing any material from the shingle. Also from the left hand vertical edge at a slight distance up from the lower edge I cut a slit 12 horizontally therefrom and from the inner end of this slit 12 cut the shingle at 60 right angles thereto downwardly toward the lower edge to form the downturned slit 13.

The length of the slit 13 may be somewhere in the neighborhood from one-quarter to three-eights of an inch in length while the length of 65 the slit 12 is substantially equal to the distance from the slit 11 to the right hand vertical edge of the shingle 10. The length of the slit 11 is substantially equal to the distance from the lower horizontal edge of the shingle 10 to the lower 70 end of the slit 13. The actual dimensions may of course be varied as desired and the above indicated dimensions are given merely to indicate the relationship between the various slits.

Referring now to Fig. 4, assuming that a left 75 hand shingle A has been laid in place, a nail 14 is driven through substantially the center point of the rectangle formed in the lower right hand corner of the shingle as bounded by the vertical and lower edges of the shingle, the slit 11 and an 80 imaginary line horizontally drawn from the top of the slit 11 to the right hand shingle edge. The next shingle B is then laid down flat on the roof deck and slipped upwardly and side-wise to cause the corner c of the shingle A to be lifted sufficient- 85 ly to permit the corner d to pass thereunder with the left hand edge of the shingle B coming over on top of the shingle A so as to have the inner end of the slit 12 approaching the upper end of the slit 11. Then the shingle B is pushed directly 90 up to have the slit 13 of the shingle B move along the slit 11 of the shingle A, which action will bring the under or lower horizontal edge of the shingle B into line with the lower edge of the shingle A. A nail 15 may then be driven through 95 the shingle B and the shingle A at the upper left corner and on into the roof deck similar to that through the shingle A to the left. Also a nail 16 may then be driven through the lower right hand corner of the shingle B.

A study of this corner lock so formed by the corners of the shingles will show that the left hand edge of each shingle is always on top of the shingle to the left as its major lap and that only that portion of the shingle to the right is 105 under the shingle to the left as is directly below the horizontal slit 12 so that there is only a very small amount of any shingle that is required to be pushed up under an adjacent shingle. Also attention is directed to the fact that by reason 110

of the short vertical slit 13 extending downwardly from the inner end of the slit 12, it is impossible to lift the lower edge E of any shingle above the upper end of the slit 11 such as might be the 5 result of a high wind since the slit 13 prevents lateral movement of the left hand edge of the shingle and the right hand edge is nailed down to the deck. Similarly should a wind strike the roof from the left hand side, the shingles will not 10 be lifted by reason of the fact that the shingles can not travel laterally again by reason of this same slit 13. To lift any shingle either from its left edge or its lower edge would mean that the part of the shingle under the next shingle to the 15 left would have to be pulled outwardly therefrom but this is impossible by reason of the engagement of the slit 13 at the upper end of the slit 11.

The shingles are laid in continuous horizontal rows and each row may be lapped to any amount 20 desired over the next row below. The amount of lap as indicated in Fig. 4 shows the approximate maximum amount of exposure to the weather that may be obtained whereas in Fig. 3 the rows are so lapped as to give from two to three 25 thicknesses of shingles over the deck. The small lap as indicated in Fig. 4, is employed where it is the intention to cover the roof with the fewest possible number of shingles and even with this small lap, there is no danger of the shingles lifting 30 by their exposed edges. Of course with the greater lap as indicated in Fig. 3, a better roof is secured and the length of the vertical edges exposed is less.

While I have above indicated that the nail 14 is 35 driven in the center of the rectangle bounded by the slit 11 to the left, it is of course entirely feasible to shift that point of nailing upwardly in the case where a joint or crack in the roof deck is encountered, it is always desirable to have 40 the nail 14 pass through the shingle below.

I claim:

1. A roof covering comprising in combination, a plurality of horizontal rows of shingles made of 45 flexible roofing material, each shingle being rectangular in shape and being provided with a vertical slit cut upwardly from the bottom edge adjacent the right vertical edge, the left hand edge of the shingle being provided with a slit cut horizontally from the edge into the shingle adjacent the bottom edge and a slit extending downwardly a short distance from the inner end of the horizontal slit, the adjacent shingles in each row being interlocked at the lower corners by having 50 the shingles straddle each other about said slits to have that part of the left edge of a shingle above its horizontal slit lap over on top of the adjacent shingle and to have the remainder of that left edge inserted under the adjacent shingle

through its vertical slit and the horizontal slit positioned above the upper end of the vertical slit which slit end is straddled by said downturned slit, and a fastening nail through each shingle to the right of said vertical slit and below the upper 80 end thereof.

2. A roof covering comprising in combination, a plurality of rows of individual shingles made of flexible roofing material and having parallel vertical edges, one of which edges of each shingle is cut to have a slit extending by a major portion horizontally into the shingle at a short distance up from the bottom edge and by a minor portion sharply downwardly, the bottom edge of each shingle having a slit cut therefrom vertically upwards adjacent the other of the said vertical edges, said shingles being interlocked one with the next adjacent shingle by straddling the corners thereof through said slits to have that portion of one shingle between its horizontal slit and the bottom edge passed through the vertical slit and under the adjacent shingle with the portion of the first shingle above the horizontal slit lapped over on top of the adjacent shingle, the one shingle being positioned to have the horizontal slit 100 above the upper end of the vertical slit in the other shingle by the length of the downturned slit, and a fastening nail through the corner of the adjacent shingle between the vertical slit and the adjacent lapped over vertical edge thereof. 105

3. As a new article of manufacture, a rectangular shingle made of flexible roofing material having a slit cut from its bottom edge upwardly spaced a short distance from a vertical edge and having a slit cut from the other vertical edge 110 inwardly spaced a short distance above the bottom edge and thence cut downwardly from the inner end, the lower end of the downturned part of the last slit being substantially at the same distance as that of the upper end of the other 115 slit from the bottom edge of the shingle.

4. A roof comprising courses of overlapping shingles, each shingle having a pair of integral flaps formed at the opposite lower corners thereof by cuts in said blanks, one of said cuts extending inwardly from one side of said blank and the other cut extending inwardly from the lower edge adjacent the opposite side of said blank, the bottom-cut flap of one shingle being adapted to be nailed to a roof, and the side-cut portion of the adjacent shingle being adapted to overlap the nailed side of said first-named shingle with its side-cut flap underlaying said first-named shingle inwardly of said nailed flap whereby a double overlapping interlock which seals said nailed flap 120 against seepage of water thereto is provided. 125
